CLAIM

The ornamental design for a rig for electrophoresis gel casting, as shown and described.

DESCRIPTION

This application is related to U.S. Design patent application Ser. No. 29/545,620, entitled "Electrophoresis Gel Cassette," and filed on a date even herewith; to U.S. Design patent application Ser. No. 29/545,633, entitled "Cassette Support Base for Electrophoresis Gel Casting," and filed on a date even herewith; and to U.S. Design patent application Ser. No. 29/545,635, entitled "Cassette Clamp for Electrophoresis Gel Casting," and filed on a date even herewith, the entire contents of each of which are incorporated by reference herein.

FIG. 1 is a front perspective view of a first embodiment of a rig for electrophoresis gel casting showing our new design.

FIG. 2 is back perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof.

FIG. 9 is a front perspective view of the rig for electrophoresis gel casting of the first embodiment in an alternative position.

FIG. 10 is a back perspective thereof.

FIG. 11 is a front view thereof.

FIG. 12 is a back view thereof.

FIG. 13 is a right side view thereof.

FIG. 14 is a left side view thereof.

FIG. 15 is a top view thereof.

FIG. 16 is a bottom view thereof.

FIG. 17 is a front perspective view of a second embodiment of a rig for electrophoresis gel casting showing our new design.

FIG. 18 is a back perspective thereof.

FIG. 19 is a front view thereof.

FIG. 20 is a back view thereof.

FIG. 21 is a right side view thereof.

FIG. 22 is a left side view thereof.

FIG. 23 is a top view thereof.

FIG. 24 is a bottom view thereof.

FIG. 25 is a front perspective view of the rig for electrophoresis gel casting of the second embodiment in an alternative position.

(Continued)

FIG. 26 is a back perspective thereof.
FIG. 27 is a front view thereof.
FIG. 28 is a back view thereof.
FIG. 29 is a right side view thereof.
FIG. 30 is a left side view thereof.
FIG. 31 is a top view thereof; and,
FIG. 32 is a bottom view thereof.
The broken lines represent portions of the rig for electro-
phoresis gel casting that form no part of the claimed design.
The broken lines form no part of the claimed design.
